UNITED STATES PATENT OFFICE.

SIMEON R. STANDISH, OF MIDDLEBOROUGH, ASSIGNOR TO HIMSELF AND
WILLIAM C. LEONARD, OF BOSTON, MASSACHUSETTS.

IMPROVEMENT IN TICKET-CLAMPS.

Specification forming part of Letters Patent No. 147,878, dated February 24, 1874; application filed
January 21, 1874.

To all whom it may concern:

Be it known that I, SIMEON R. STANDISH, of Middleborough, county of Plymouth and State of Massachusetts, have invented a Device for a Price-Ticket Clamp, of which the following is a specification:

The invention is a device for holding cards, on which the prices of articles for sale are marked.

The device is composed of three parts, viz: A clip, A, a clamp, B, and a thumb-screw, C. The clip A, (see Fig. 1 in the drawing,) is composed of two thin crescent-shaped metallic plates, soldered or joined at the bow of the crescent, leaving the horns free or separate to admit a card between them. Said clip is shown in Fig. 1 holding a card. The clamp B is a narrow metallic plate, with one end fastened to the front of the clip, doubling and embracing the clip on both sides at the bow, as shown in drawing, Fig. 1. The shape of said clamp is seen in Fig. 2. The thumb-screw C goes through the clip at the bow and that part of the clamp embracing the clip, and thus

bears upon the side of a box or basket, taking a firm hold of the box or basket between the screw and the extended end of clamp.

Fig. 2 gives a side view of the three parts, A, B, and C.

The clip is composed of elastic metallic plates, and it is obvious that the same might be fastened directly to the thumb-screw.

What I claim as my invention, and desire to secure by Letters Patent, is—

A ticket-clamp composed of a clip, A, consisting of two thin crescent-shaped metallic plates joined at the bow, and having the horns free or separated to receive the ticket, a clamp, B, consisting of a narrow metallic plate doubled, and embracing the clip on both sides at the bow, and a thumb-screw, C, which passes through the clamp and clip at the bow, and thus bears against the side of a box or basket, the whole being constructed and combined substantially as described.
